UNITED STATES PATENT OFFICE.

MORGAN L. WILLIAMS, OF JOHNSTOWN, PENNSYLVANIA.

DESIGN FOR A BRICK.

SPECIFICATION forming part of Design No. 26,848, dated March 30, 1897.

Application filed February 9, 1897. Serial No. 622,669. Term of patent 7 years.

To all whom it may concern:

Be it known that I, MORGAN L. WILLIAMS, a citizen of the United States, and a resident of Johnstown, in the county of Cambria and State of Pennsylvania, have invented certain new and useful Designs for Runner-Bricks; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a representation of a perspective view of runner-brick. Fig. 2 is a side elevation of same. Fig. 3 is a second side elevation of brick.

This invention has relation to a certain new and original design for runner-bricks; and it

consists in the novel form and configuration thereof, all as hereinafter described, and illustrated in the accompanying drawings.

The design more particularly consists in a brick of polygonal form with parallel upper and lower faces A and B and alternating prismatic and pyramidal lateral faces C and D. The upper face A has therein a central circular cavity E and the pyramidal faces E, having each an opening F.

What I claim is—

The design for a runner-brick substantially as herein shown and described.

In testimony whereof I affix my signature in presence of two witnesses.

MORGAN L. WILLIAMS.

Witnesses:

GEORGE H. PARMELEE,
PHILIP C. MASI.
